GUIDE FOR ENDLESS TRACKS

Edwin L. Allen and Harold B. Muster, Cleveland Heights, Ohio, assignors to Rudolph I. Schonitzer, Shaker Heights, Ohio

Application September 3, 1941, Serial No. 409,394

14 Claims. (Cl. 305—10)

This invention relates to improvements in a guide especially adapted for use with a flexible, endless, self-laying track of a type used for tractors, tanks, trucks and the like.

This invention is an improvement of the guide disclosed and described in Patent No. 2,107,490 granted February 8, 1938, to Robert Mayne. The guide shown in this prior patent was adapted for production only by forging, resulting in a number of objections and disadvantages. The production was relatively slow and costly. It was difficult to get the necessary hardness for withstanding the abrasive action of sand and water encountered during the use of tracks of this type because the forging had to be kept soft enough for subsequent machining operations and if treated for hardness after machining, distortion would occur. Accuracy of shape and cross section and the small clearances desired could not be held within desirable limits due to the inherent characteristics of commercial forging processes. Consequently vital sections of the guides were sometimes smaller than desired, thus increasing the likelihood of breakage in service. The surface of the forgings was relatively uneven and rough, thus accelerating the cutting action of the abrasive materials encountered in service and leading to greater wear.

An object of the present invention is to overcome the above objectionable features and disadvantages. Our improved guide may be made of metal stampings so that the production is relatively rapid and inexpensive. Suitable hardness may be provided in the finished product because no machining is necessary after fabrication. Accuracy of shape and cross section can be held within the desired limits so that no weak sections are produced. The surface of the finished product is relatively even and smooth thus diminishing the abrasive action when the product is in service.

Other advantages, impossible in the prior device, are produced by arranging a plurality of metal stampings in such a manner as to reinforce each other when they are finally assembled into the completed guide. Also interengaging positioning surfaces have been provided between the guide members and the track so that when these members and track crossbars are clampingly secured together the positioning surfaces are wedged tightly together thus preventing movement of the guide members. Another improvement is the provision of deformations in the metal plates of which the guide members are formed extending in directions to provide the

desired beam strength for transmitting lateral track thrust from one guide member to the other. Still another advantage is the provision of novel interengaging positioning parts on the crossbar and on the guide member so that the guide members are firmly positioned on the track. Another advantage is the provision of abutments on the crossbars positioned to limit movement of the guide members transversely of the path of track movement and strong guide lug portions interengaging between adjacent guide members so that these abutments and guide members resist localized forces tending to move a portion of the track out of a rectilinear path.

Other objects and advantages of the present invention will appear from the accompanying drawings and description and the essential features thereof will be set forth in the claims.

In the drawings,

Fig. 1 is a side elevation of a portion of an endless track equipped with our improvement, a portion being cut away to show the application of the improved guide member.

Fig. 2 is a bottom view of a portion of the track of Fig. 1 as viewed generally from the line 2—2, Fig. 1, and shows the application of several of the interfitting guides.

Fig. 3 is an enlarged side elevation of one guide member partly in section taken along the line 3—3 of Fig. 5.

Fig. 4 is a transverse sectional view through a guide member showing its application to a track crossbar and taken along the line 4—4 of Fig. 5.

Fig. 5 is a plan view of the guide of Figs. 3 and 4 as viewed along the line 5—5 of Fig. 3.

Fig. 6 is a transverse sectional view taken along the line 6—6 of Fig. 5.

Fig. 7 is a transverse sectional view taken along the line 7—7 of Fig. 3.

Fig. 8 is a detail plan view of a locating channel which forms the bottom portion of the guide member.

Fig. 9 is a side elevational view of the channel of Fig. 8, taken partly in section along the line 9—9 of Fig. 8.

Fig. 10 is a side elevation partly in section, along line 10—10 of Fig. 12, of a modified form of guide member.

Fig. 11 is a central sectional view through the guide of Fig. 10 taken along the line 11—11 of Fig. 12.

Fig. 12 is a top plan view of the guide shown in Figs. 10 and 11.

It has not been thought necessary to illustrate 55 more of the endless track here involved than the

portions shown in Figs. 1 and 2 for the reason that the present invention is applicable to a well-known type of endless track, such as that shown in the Mayne patent referred to above. Such a track comprises parallel flexible endless bands 15 and 15' connected together by metal crossbars 16 spaced at regular intervals and preferably embedded in the rubber of the endless bands so as to form a firmly united flexible endless self-laying track. This track as shown in the above referred to patent passes over suitable idlers and beneath load bearing wheels or rollers and is generally driven by a sprocket, the teeth of which engage between the endless bands in the spaces between the crossbars 16.

The present invention relates generally to improvements in the guide members indicated generally at 17 which are attached to the crossbars in the space between the bands 15 and 15'. The purpose of these guide members is to maintain alignment of the flexible track against localized thrust tending to move portions of the track transversely to the path of track movement. Such lateral thrust occurs when the vehicle is travelling on the side of a hill or when it hits obstacles tending to thrust a portion of the track sideways.

The track construction and the crossbars are generally of the form shown in the above mentioned Mayne patent. Each crossbar as best seen in Fig. 4 comprises two portions 16a and 16b which are held together by any suitable means but here shown as connected by the stud 16c which extends from the portion 16a through an opening 16d in the portion 16b and all held together by the nut 18 which may also serve to clamp a guide member in position. The two portions of the crossbar clampingly engage the endless cables 19 which, as shown in the Mayne patent, form a part of the endless bands 15 and 15'. The crossbar portion 16b is preferably provided with sprocket engaging abutments 16e.

The guide member shown in Figs. 1 to 9 inclusive comprises two outer plate halves 20 and 20', an inner plate 21, and a locating channel 22 all welded together into a unitary rigid assembly. In general the guide member is of H-form with the central portion of the H being a flat portion parallel to the inner face of the crossbar 16 and secured thereto on the stud 16c. The plate member 21 is generally U-shape in central transverse section having a central portion 21a and side flange portions 21b in planes at right angles to the central portion. Relief cuts 34 in plate 21 are for the purpose of facilitating the bends between portions 21b and 21a. The outer plate members 20 and 20' are alike and comprise side walls 20a forming the sides of the H-form and bent inwardly along their peripheral edges as shown at 20b to reinforce the edges of the guide lug portions so as to form stronger beam members. The edge flanges 20b also provide a rounded leading edge for the guide where it slides into contact with the wheels and also the adjacent guides. Referring to Fig. 2, it will be seen how the parallel sides of the H-form are spaced more closely together at one end of each guide member so that they enter into the more widely spaced guide lug portions of the adjacent guide member with slight clearance. Thus these guide lug portions slidingly interengage permitting flexing of the track as it moves about its idlers and sprockets but maintaining alignment in the path of travel of the track. The forces tending to laterally displace a portion of the

endless track are thus transmitted between the slidingly engaged lug portions of adjacent guide members. This causes the guide lug portions to act as cantilever beams and this beam action is greatly assisted by the flange deformations 20b. Other deformations at 20c where the plates 20 and 20' rest on the crossbar aid this beam action and at the same time give better bearing against the abutments 23 on the crossbar. These plates 10 are also provided with tongues 20d extending inwardly between positioning abutments 23 on the crossbar member 16b.

Referring to Fig. 4, the hollow spaces above the deformations 20c give a box beam construction at this point which is very strong. Additional strength for the guide lug portions which extend outwardly from the central portion is provided by outwardly extending deformations 25 of the plates 20 and 20', best seen in Figs. 20 3, 5 and 6. Other strengthening deformations are provided at 26 by bending portions of the plate 21 inwardly as best seen in Figs. 5 and 6. These deformations are inclined inwardly toward the central portion of the guide member so 25 as to direct the abutments 16e into proper engagement with the sprocket teeth. Other deformations 33 are folds of metal struck up from plate 21 and extending diagonally across the bends connecting portions 21b and 21a.

Considering this construction and referring to Fig. 2, it will be apparent that any thrust on one of the guide members will be carried by a strong beam construction aided by strengthening deformations 25 and 26 from the central portion 30 of one guide member to the end of the narrower of its lug portions and there transmitted to the wider lug portions of the next guide member which in turn are strengthened at 33 where they join their associated central portion. Thus 35 the entire track is kept in line and forces are transmitted without damage to the guide lugs.

Between the tongues 20d and the inner plate 21 lies the locating channel 22 which is best seen in Figs. 8 and 9. This channel has a web 45 22a which may be provided with small spaced projections 24 on opposite sides thereof so that when the parts are assembled and subjected to electrical current under pressure these projections will melt and weld the associated parts together. 50 The flanges 22b extend downwardly and lie outside of the positioning abutments 23 on the crossbar. It will be noted that the coating surfaces, 23a of the crossbar abutment and 22c of the locating flange, are wedge-shaped and so engage each other as the guide member is pulled 55 into final position on the crossbar by tightening of the nut 18 that these parts are tightly wedged together so as to give a very satisfactory engagement between the guide member and the track. It will be noted also from Fig. 3 that the outermost surfaces of the flanges 22b snugly engage the inner faces of the sprocket engaging portions 16e which aids in positioning the guide member on the crossbar.

It will be noted from Fig. 4 that the plates 60 when assembled and welded together have large areas secured to and reinforcing each other, i. e., the flanges 21b of the inner plates engage the plates 20 and 20' over a large area and are secured thereto by a sufficient number of welded spots. The line 35 indicates a slight break in plate 21 to conform to plate 20 or 20'. As best seen in Figs. 5 and 7 the flanges 21b of the inner plates are flattened against the plates 20 and 20' in the areas welded together. As previously

explained the central portion of plate 21, the tongues 26d and the locator channel 22 are firmly secured together over a large area.

The guide member is secured to the crossbar on stud 16c which passes between tongues 20d and through centrally located apertures in channel 22 and plate 21. A lock washer 32 and nut 18 are the securing means.

Referring now to Figs. 10, 11 and 12, a modified form of the device is shown having many features in common with the first described form and therefore similar parts have been given similar reference characters. The inside plate member 21 is substantially identical with the member previously described. The outside plate members 20 and 20' are very nearly the same except that they omit the deformations 20c and the tongues 20d are wider, extending to the line 27 where the inner end of the tongue abuts against a shoulder 28 extending squarely across the crossbar 16. It will be understood that as in the previously described form the parts 20, 20' and 21 are first formed and are then electrically welded together under pressure so as to secure broad surfaces of the members together. Various spots where welding occurs have been indicated in Figs. 10 and 11 but it will be understood that these spots may be differently placed, it only being necessary that the meeting surfaces be well secured together.

Positioning abutments 16f are here formed on the upper surface of the crossbar member 16b spaced so as to receive snugly the outer faces of the plates 20 and 20' as indicated in Figs. 11 and 12. It will be noted that these abutments together with the shoulders 28 form definite positioning parts holding the guide member firmly on the crossbar 16 and absorbing any side thrust. This side thrust is the important force resisted by the guide members. Inasmuch as the guide lug portions extending outwardly on each side of each crossbar transmit forces along the line of guide members as explained in connection with Fig. 2, the abutments 16f on the various crossbars and the guide lug portions keep the entire track in line.

Two parallel grooves 29 are cast or forged in the crossbar member 16b so as to render easier the machining of the surface 30 against which the central portion 21a of the inner plate rests. The substantially parallel side edges of this central portion 21a as indicated at the point 31 in Fig. 10 engage against the inner faces of the sprocket engaging abutments 16e, thus preventing movement of the guide member lengthwise of the track. It will be understood, as in the first described modification, that the parts which have here been described in connection with the second modification are formed of metal stampings welded together, heat treated if necessary and then assembled on the stud 16c with a lock washer 32, the entire assembly being pulled down into position and held there by the nut 18.

It will be understood that the deformations 33 shown and described in connection with the first form may be used in exactly the same manner in plate 21 of the second form shown in Figs. 10 to 12.

What we claim is:

1. In a flexible endless self-laying track movable in a path and having crossbars spaced along said track transversely to said path of movement, abutments on said crossbars generally parallel to said path and normally in alinement, and substantially rigid guide lugs fixed on said

crossbars engaging said abutments, the guide lug on each crossbar overlapping the lugs on adjacent bars with slight clearance, whereby said lugs and abutments maintain said track in alinement resisting localized forces tending to move a portion of said track out of said path.

2. The combination of claim 1 wherein said guide lugs are formed of metal plates having strengthening deformations extending along overlapping portions of said lugs to form strong beam sections for coacting lug portions transmitting thrust acting transversely of said path.

3. In the combination of a flexible endless self-laying track having crossbars spaced at regular intervals and having guide members on said crossbars interengaging one with another, coacting positioning deformations on said crossbars and guide members, means for clampingly securing said members to said bars, and coacting wedge-shape surfaces on said members and bars moved into tight-fitting engagement by action of said securing means.

4. In the combination of a flexible endless self-laying track movable in a path and having crossbars spaced along said track transversely to said path of movement, a guide member comprising a central portion secured to a crossbar and substantially parallel guide lug portions extending generally parallel to said path, said guide member comprising inner and outer metal plates welded together, and coacting interengaging parts on said crossbar and one of said plates for positioning said member on said bar.

5. In a flexible endless self-laying track movable in a path and having crossbars spaced along said track transversely to said path of movement, said crossbars being adapted to engage a driving sprocket, guide members one for each crossbar and comprising a central portion secured to the crossbar and substantially parallel guide lug portions extending generally parallel to said path, the lug portions of one guide member slidingly engaging the lug portions of adjacent guide members, said lug portions comprising a plurality of metal plates, and one of said plates having deformations inclined inwardly from the ends of said lug portions toward said central portion for guiding said crossbar into proper engagement with the sprocket teeth and for strengthening said plates.

6. In a flexible endless self-laying track movable in a path and having crossbars spaced along said track transversely to said path of movement, said crossbars being adapted to engage a driving sprocket, guide members one for each crossbar and comprising a central portion secured to the crossbar and substantially parallel guide lug portions extending generally parallel to said path, the lug portions of one guide member slidingly engaging the lug portions of adjacent guide members, and said guide members comprising a plurality of plates welded together, there being a hollow space between said plates strengthening said guide member.

7. In a flexible endless self-laying track movable in a path and having crossbars spaced along said track transversely to said path of movement, said crossbars being adapted to engage a driving sprocket, guide members one for each crossbar and comprising a central portion secured to the crossbar and substantially parallel guide lug portions extending generally parallel to said path, the lug portions of one guide member slidingly engaging the lug portions of adjacent guide members, and said guide members comprising a plu-

rality of plates welded together, said plates having strengthening deformations extending along said lug portions.

8. In a flexible endless self-laying track movable in a path and having crossbars spaced along said track transversely to said path of movement, said crossbars being adapted to engage a driving sprocket, guide members one for each crossbar and substantially parallel guide lug portions extending generally parallel to said path, the lug portions of one guide member slidably engaging the lug portions of adjacent guide members, and said guide members comprising a plurality of plates generally parallel to each other and welded together, said plates having strengthening deformations, said deformations being on different plates and complementary to each other in their strengthening effect.

9. In a flexible endless self-laying track movable in a path and having crossbars spaced along said track transversely to said path of movement, said crossbars being adapted to engage a driving sprocket, guide members one for each crossbar and comprising a central portion secured to the crossbar and substantially parallel guide lug portions extending generally parallel to said path, the lug portions of one guide member slidably engaging the lug portions of adjacent guide members, each of said guide members having an inner plate U-form in transverse section through said central portion and having integral wing extensions along said lug portions, each of said guide members having two outer plates L-form in transverse section through said central portion and having integral wing extensions along said lug portions, and said inner and outer plates being welded together at said central portions and along said lug portions.

10. The combination of claim 9 wherein said crossbar is provided with parallel abutments and the central portions of said outer plates lie between said abutments.

11. The combination of claim 9 wherein said cross bar is provided with parallel abutments and the central portion of said inner plate lies between said abutments.

12. The combination of claim 9 wherein said crossbar is provided with an abutment centrally of said guide member, and the central portions of said outer plates engage opposite sides of said abutment.

13. The method of forming, for flexible endless self-laying tracks, guide members having inter-engaging guide lug portions and track engaging portions, comprising die-forming deformable metal sheets to the desired dimensions and with strengthening configurations for said lug portions, forming other metal sheets for said track engaging portions, and assembling said sheets and welding them to a composite whole in which one sheet reinforces the other.

14. In the combination of a flexible endless self-laying track movable in a path and having crossbars spaced along said track transversely to said path of movement, a guide member having a central portion adapted to be secured to a crossbar and also having substantially parallel guide lug portions extending generally parallel to said path of movement and comprising inner and outer metal plates welded together, one of said plates being recessed in dish form and the other of said plates lying in the recess of said first mentioned plate.

EDWIN L. ALLEN.
HAROLD B. MUSTER.
